UNITED STATES PATENT OFFICE.

JAMES M. DODGE, OF PHILADELPHIA, PENNSYLVANIA.

CHAIN.

SPECIFICATION forming part of Letters Patent No. 761,037, dated May 24, 1904.

Application filed March 17, 1904. Serial No. 198,655. (No model.)

To all whom it may concern:

Be it known that I, JAMES M. DODGE, a citizen of the United States, residing in Philadelphia, Pennsylvania, have invented certain Improvements in Chains, of which the following is a specification.

My invention relates to that class of chains in which the links are coupled by and articulate upon pivots.

One of the objects of my invention is to provide the links of such chains with larger bearing-surfaces upon the pivot-pins than in prior constructions of such chains, a further object of the invention being to provide means whereby bending strains upon the pivot-pins of such chains will be avoided, and a still further object is to so construct the chain that the pivot-pins shall be free to turn within the bearings, so as to prevent uneven wear of said pins.

These objects I attain in the following manner, reference being had to the accompanying drawings, in which—

Figure 1 is a longitudinal sectional view of a chain illustrating my invention, the section being on the line 1 1, Fig. 2. Fig. 2 is a sectional view on the line 2 2, Fig. 1. Figs. 3 and 4 are detached perspective views of the links shown in Figs. 1 and 2. Fig. 5 is a sectional view showing a chain similar to that shown in Fig. 1, save that it does not employ "bushings." Fig. 6 is a view of a chain made up of links all of the same shape. Fig. 7 is a view of a chain made up of a series of link elements without the bushings. Fig. 8 is a sectional view on the line 8 8, Fig. 9, in which two bushings are used. Fig. 9 is a section on the line 9 9, Fig. 8. Fig. 10 is a view of a toothed chain to which my invention is applied. Fig. 11 is a sectional view showing two links pivoted together in such a manner that the pivot-pin is not subjected to unbalanced strain, the links having integral extensions. Fig. 12 is a section on the line 12 12, Fig. 11. Fig. 13 is a construction similar to Fig. 11, with the exception that the lateral extension is in the form of a bushing. Fig. 14 is a view illustrating a hooked link which can be used in carrying out my invention, and Fig. 15 is a view of a modification of the chain shown in Fig. 5.

In this description the term "link" includes 50 either a link made in one piece, as shown, for instance, in Fig. 4, or a link composed of two or more separate pieces or "link elements," as shown, for example, in Fig. 7, or such a link composed of two or more separate pieces 55 with interspacing-washers, such as shown in Fig. 8.

Referring now to Figs. 1 to 4, inclusive, A is a link composed of two link elements A' A', and B is in the present instance a single-piece 60 link, although (see Fig. 6) two link elements B' B' may be placed together, so as to form the link B. Links A and B are coupled by and articulate upon a pivot-pin D, which is itself free to rotate, so that the wear upon the 65 pin will be distributed over its entire surface.

Each of the link elements A' A' composing link A has at each end an opening a for the passage of a pivot-pin D, and within each opening a projects a segmental bearing a', 70 which also projects laterally from the link element, so that the two bearings a' a' form together a continuous segmental seat extending across the entire link A, as shown in Fig. 1.

Link B has at each end similar pivot-pin 75 openings b b and segmental bearings b' projecting within said openings and also projecting laterally on both sides of the link, so that when the two links A and B are pivoted together, as shown in Figs. 1 and 2, the segmental projections a' at one end of the link elements A' A', constituting link A, will project into and together form a bearing extending across link B, while the laterally-projecting portions of the bearing b' of link B will 80 project one into and across one of the link elements A' and the other into and across the other element A' of link A, the bearings a' a' b' b' then constituting substantially continuous opposite bearings extending the width of 85 link A.

In that particular form of my invention illustrated in Figs. 1 and 2 there are introduced between pivot-pin D and bearings a' a' a detachable segmental bushing E and between the 95 pivot-pin D and bearing b' a similar segmental bushing F, flanges e of bushing E overlapping bearings b' and flanges f of bushing F over-

lapping bearings a' , so that the bushings are held in place upon and move with the bearings in the motion of the links, as will be apparent on reference to Fig. 2. Although I prefer to employ these detachable bushings, it will be obvious that they may be dispensed with and that, as illustrated in Figs. 5 and 6, the segmental bearings a' and b' may be allowed to bear directly upon pivot-pin D. In either case it will be observed that the bearings of each link will perform both that function and also the function of limiting the pivotal movements of the bearings of the adjoining link. The bushings and the links are held laterally by caps d d , which are secured to a transverse rod d' , extending through the pivot-pin D. This construction, however, I do not claim in this application, as it forms the subject of a separate application filed by me April 5, 1904, Serial No. 201,701.

It will be understood that any suitable means may be provided for holding the pin and link elements against lateral movement.

In Figs. 7 and 8 I have illustrated my invention as applied to a chain composed of links each of which is made up of a series of flat link elements, the elements of one link alternating with those of the adjoining link, as shown. In chains of this character the link elements are usually so narrow that in the ordinary construction of such chains they wear away very rapidly at the pivot-openings or they cut into the pivot. My invention obviates these objections to such chains by providing each compound link with a continuous pivot-pin bearing of substantially the full length of the pivot-pin.

In Fig. 7 I have shown a chain in which link A is composed of link elements A^3 A^3 and link B of three link elements B^3 B^3 B^3 . Each link element A^3 has segmental bearings a^3 projecting into the pivot-pin aperture and each extending laterally from its link element, so as to project into the pivot-pin openings of link elements B^3 , while said link elements B^3 have corresponding segmental bearings b^3 projecting into their pivot-pin openings and each extending also laterally from its link element, so as to project into the pivot-pin openings of link elements A^3 of link A. The bearing-pieces a^3 of link A and the bearings b^3 of link B thus form practically continuous pivot-pin bearings extending the full length of the pivot-pin and width of the chain.

In the constructions thus far illustrated and described the bearings, with their lateral extensions, are shown as integral with the links; but in some cases, as where the links or link elements are punched from blanks, it may be desirable to make these segmental bearings separate from the links. Figs. 8 and 9 show a form of chain in which said bearings consist of detachable segmental bushings E' F', extending across the links and the full length of the pivot-pin D ^{4} and forming opposite bear-

ings upon the latter. The segmental bushing E' fits snugly between projections e' within the pivot-pin openings of link elements B ^{4} , while bushing F' fits snugly between projections f' in the pivot-pin openings of link elements A ^{4} A ^{4} , and the pivot-pin openings are of a size allowing the bushings E' and F' and the links to which they are respectively attached to move upon the pivot-pin to an extent limited by the projections e' and f' . Washers c , interposed between the link elements, prevent the latter from coming into frictional contact with each other and serve to increase the amount of bearing-surface of the chain upon its pivot-pins.

Although I prefer to attach the bushings to each of the link elements, as shown in Figs. 8 and 9, it will be evident that without departing from my invention said bushings may be attached to a single element of the series, the pivotal motions of the other elements being limited by coupling them to that element to which the bushing is attached.

In Fig. 10 I have shown the application of my invention to a type of chain used to a considerable extent as a drive-chain and known as a "silent" chain, the links A ^{5} and B ^{5} of this chain having teeth which engage the teeth a^5 and b^5 of a sprocket-wheel over which they pass. These chains are made up of a series of flat elements, as shown in Fig. 8, and in chains of the kind as heretofore constructed the strains placed upon them in use result in rapid wear of the link elements around the pivot-pin opening or in wear or cutting of the pivot-pin. By the application to such a chain of bushings such as illustrated in Figs. 8 and 10 these objections are overcome. I do not, however, claim the particular construction of chain shown in Figs. 8, 9, and 10 in this application, said construction being the subject of another application filed by me on the 1st day of April, 1904, Serial No. 201,123.

While my invention is particularly applicable to the class of chains known as "drive-chains," it may be applied to other forms of chain, and in Figs. 11 and 12 I have illustrated one of the simplest forms of chain to which the invention can be applied. In these views the link A ^{7} has a pivot-pin opening which also receives lateral projection b^7 of link B ^{7} , the pivot-pin opening of the latter link likewise receiving both the pivot-pin D ^{7} and the lateral projection a^7 of link A ^{7} , the pivot-pin openings being of a size to allow of the required pivotal play of the bearings a^7 b^7 , which extend substantially the entire length of the pivot-pin and form substantially coextensive opposite bearings upon the latter.

Fig. 13 shows a chain construction similar to that of Fig. 11, save that the bearings upon the pivot-pins instead of consisting of integral parts of the links consist of bushings E ^{8} F ^{8} , the former attached to link B ^{8} and the latter attached to link A ^{8} . In Fig. 14 I have

shown a view of a link A⁶, having a hooked end a⁶ instead of a closed end, as shown in the other figures, leaving an opening c' for the pivot-pin.

5 It will be observed that in each of the above-described examples of my invention the links have a bearing upon the pivot-pin extending substantially the whole length of the latter and practically continuous and that these co-extensive opposite bearings result in a balanced chain in which the objection to bending strains upon the pivot-pin is avoided. This last-named advantage can be gained in another modification of my invention, (illustrated in 15 Fig. 15,) in which a central link B⁹ has lateral projections b⁹, forming the only bearing for the link and side link elements A⁹, having openings to receive the pivot-pin and lateral projections of the central link, but not provided with lateral projections.

In the following claims, 1 to 8, both inclusive, the terms "link" or "chain-link" are used to signify and are to be understood as covering and including either a single-piece link or 25 one of the elements of a compound link, such as hereinabove shown and described. In the remaining claims the said terms "link" or "chain-link" are used to signify and are to be understood as covering and including a complete link, whether of one piece or compound 30 of two or more elements, save where the claim is specifically limited to a compound link.

I claim as my invention—

1. As a new article of manufacture, a chain-link having a lateral projection forming an extended bearing for a pivot-pin, and having an opening adapted to receive said pivot-pin and the lateral projection of an adjoining link, substantially as described.

40 2. As a new article of manufacture, a chain-link having a lateral segmental projection forming an extension of the bearing of the link for a pivot-pin and having an opening adapted to receive said pivot-pin and also to receive, and allow for pivotal play of, the lateral segmental projection of an adjoining link, substantially as described.

45 3. As a new article of manufacture, a chain-link having a pivot-pin opening and a segmental pivot-pin bearing projecting within said opening, and also extended laterally therefrom, substantially as described.

4. As a new article of manufacture, a chain-link having a segmental bearing projecting 55 within the opening for the pivot-pin, and also extending laterally from the link, so as to increase the bearing thereof upon the pivot-pin, the said pivot-pin opening of the link being of sufficient size to admit and allow to swing 60 upon the pin, the laterally-extended portion of the segmental bearing of an adjoining link, substantially as described.

5. As a new article of manufacture, a chain-link having an opening for a pivot-pin, and 65 an integral segmental bearing for said pin,

projecting within, and also extending laterally from said opening, substantially as described.

6. As a new article of manufacture, a chain-link having at each end an opening and a segmental bearing for a pivot-pin, and a lateral 70 extension of said bearing, substantially as described.

7. As a new article of manufacture, a chain-link having an opening for a pivot-pin, a segmental bearing for said pin formed within said 75 opening, and a lateral segmental projection on each side of the link, said projections forming continuations of said bearing, substantially as described.

8. A chain-link having a pivot-pin opening, 80 and a segmental projection within said opening, and constituting a pivot-pin bearing and a stop to limit the motions of an adjoining link, substantially as described.

9. The combination of two links pivotally 85 connected, and each having a lateral projection, and an opening into which the lateral projection of the other link extends, said projections forming opposite and coextensive bearings for the pivot-pin, substantially as 90 described.

10. The combination of two links having opposite and coextensive segmental bearing-surfaces with a pin free to turn upon said bearing-surfaces, substantially as described. 95

11. The combination in a chain, of two links and a pivot-pin therefor, each link having a segmental lateral projection forming an extended bearing on the pivot-pin, and an opening through which pass both the pivot-pin and 100 the segmental lateral projection of the adjoining link, substantially as described.

12. The combination with a pivot-pin, of two links, each having a lateral projection and an opening into which the lateral projection 105 of the other link extends, and each link with its lateral projection having a bearing upon substantially the full length of the pivot-pin, substantially as described.

13. The combination with a pivot-pin, of two links, each having a lateral segmental projection and an opening into which the lateral projection of the other link extends, and a pivot-pin, each link with its lateral projection presenting a substantially continuous 115 bearing upon the entire length of the pivot-pin, substantially as described.

14. The combination of two links and a pivot-pin, each link having a lateral segmental projection and an opening into which the lateral projection of the other link extends, the links with their lateral projections presenting opposite and substantially coextensive bearings on the pivot-pin, substantially as 120 described. 125

15. The combination of two links with a pivot-pin therefor, each link having a lateral segmental projection and an opening into which the lateral projection of the other link extends, the links with their lateral projec- 130

tions presenting opposite pivot-pin bearings of substantially equal length across the links, substantially as described.

16. The combination of two links, a pivot-pin coupling said links, a segmental lateral projection of one link extending into the pivot-pin opening in the other link, and having a bushing forming a bearing-surface upon said pin, substantially as described.

17. The combination in a chain, of two links, a pivot therefor, each link having a lateral extension forming a continuation of the bearing of the link, a segmental bushing carried by each link, said bushings being opposite each other and coextensive, substantially as described.

18. The combination in a chain, of two links and a pivot-pin connecting the same, one of said links having a lateral projection on each side, and being pivoted between the two elements which compose the other link, and each

of which elements has a lateral projection on one side, the lateral projections of one link entering and moving pivotally within the pivot-pin opening of the other link, all substantially as described.

19. The combination in a chain, of two links and a pivot-pin connecting the same, one of said links being situated between two elements composing the other link, and each link carrying a bushing which extends through the pivot-pin openings of both links, and bears and moves upon the pivot-pin, substantially as set forth.

In testimony whereof I have signed my name to this specification in the presence of two subscribing witnesses.

JAMES M. DODGE.
